UNITED STATES PATENT OFFICE.

JOHN FOSTER STEPHENSON, OF GLENFERRIE, VICTORIA.

SUPPORTING-FRAME FOR BEDSTEADS.

SPECIFICATION forming part of Letters Patent No. 644,781, dated March 6, 1900.

Application filed August 21, 1899. Serial No. 727,891. (No model.)

To all whom it may concern.

Be it known that I, JOHN FOSTER STEPHENSON, a subject of the Queen of Great Britain, and a resident of Cranmore street, Glenferrie, in the Colony of Victoria, have invented certain new and useful Improvements in or Connected with the Supporting-Frames of Bedsteads, of which the following is a specification:

10 I provide what I have herein termed a "socket-piece"—namely, a metal boss having a cavity to be fitted upon a bedstead-post—and a shoe or box formed in it to receive the wooden rail of a spring-mattress and with 15 novel means of securing the rail in place. In some cases the post has a cone formation to receive the socket-piece and means of locking same in position. By the use of my invention the ordinary metal dovetailed rails 20 are dispensed with and a cheaper and better construction is provided.

In order to make my invention clear, I shall now refer to the accompanying sheet of drawings, in which—

25 Figure 1 shows a plan of a post provided with socket-piece; Fig. 2, a vertical section of same; Fig. 3, an elevation of a socket-piece detached from the standard; Fig. 4, an elevation of portion of the post, showing the cone for the socket-piece. Fig. 5 shows the end frame of a bedstead to which my invention is applied, one of the socket-pieces being shown in position for packing and one in position to receive the rail of a spring-mattress. Fig. 6 30 shows a form of connection of a socket-piece and a bed-post in which the cone formation is dispensed with and showing also means for holding the rail in the shoe. Fig. 7 shows a plan of the shoe portion of the socket-piece 35 with the means for holding the rail in the shoe.

In the drawings, *a* represents a socket-piece in which a conical cavity or socket *b* is formed. Two or more keyways are formed in this cavity, preferably one at the forward portion *c* and one at each side *d e*. The socket-piece is formed with the box or shoe *f* to receive the rail of a spring-mattress, said socket-piece having a closed bottom and sides and an open 40 top. A lateral holding-tooth *g* is provided on the bottom of the socket to form a hold upon the rail, and the said bottom has a hole *l* to

receive the bolt, which secures the rail in position.

h represents a post or standard of a bedstead and which has secured upon it or made intimate with it a metal cone *i*, which is arranged to fit into the cavity of the socket-piece aforesaid. This cone has a key *k* upon it, which corresponds with the keyways *c d e* 55 60 and is adapted to enter either of said keyways.

In securing together a bedstead provided with the improvements the post *h* is passed through the conical cavity *b* of the socket-piece until stopped by the cone *i* upon said post, the socket-piece being thus supported. The key *k* being brought into position in the keyway *c* (if so desired) will lock the joint, with the shoe in position to receive the frame 70 of the mattress or a rail of the bed.

When bedstead-frames provided with my improvements are to be packed, the socket-pieces may be raised off their cones and turned around into the position shown at the left in Fig. 5, the key *k* in this case resting in the keyway *e*. I may employ two keyways only—namely, one at the front and one at one side of the socket.

I prefer the means illustrated on Figs. 6 and 7 for holding the rails of a spring-mattress in their respective shoes. *l* represents the bolt-hole before referred to, through which passes a bolt which is passed through the rail, such bolt being secured by a nut beneath the 85 shoe. *m* represents a stud, which is set upon the shoe in front of and substantially in line with the bolt-hole *l*. This stud may have a slightly-conical taper. The stud enters a corresponding recess formed on the under side 90 of the rail, so that the bolt and stud will together form a secure hold upon the rail to prevent any movement thereof within the shoe.

Having now particularly described and ascertained the nature of my said invention and in what manner the same is to be performed, I declare that what I claim is—

1. The combination with a standard having a cone formed thereon and provided with a key, of a socket-piece having a conical cavity arranged to fit over said cone, and provided with a plurality of keyways arranged to receive said key, and means carried by said

socket-piece for engaging a rail, substantially as set forth.

2. The combination with a standard having a cone formed thereon and provided with a key, of a socket-piece having a conical cavity arranged to fit over said cone, and provided with a plurality of keyways arranged to receive said key, a shoe formed with said socket-piece and having a closed bottom and sides

and an open top, and a stud projecting from the bottom of said shoe, substantially as set forth.

Signed at Melbourne, in the Colony of Victoria, Australia, this 17th day of July, 1899.

JOHN FOSTER STEPHENSON.
